(57) **CLAIM**

The ornamental design for an umbrella handle, as shown and described.

DESCRIPTION

FIG. 1 is a perspective view of an umbrella handle showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the umbrella handle where the umbrella handle is in a configuration of use.

The broken lines in the drawings depict portions of the umbrella handle that form no part of the claimed design. The other broken lines showing an umbrella body in FIG. 9 are for the purpose of illustrating environment and form no part of the claimed design.
